UNITED STATES PATENT OFFICE.

DANIEL L. BECKER, OF OAKLAND, CALIFORNIA.

DESIGN FOR A VEHICLE-TIRE.

59,699.

Specification for Design.

Patented Nov. 22, 1921.

Application filed May 25, 1921. Serial No. 472,603. Term of patent 14 years.

To all whom it may concern:

Be it known that I, DANIEL L. BECKER, a citizen of the United States, and a resident of Oakland, county of Alameda, State of California, have invented a new, original, and ornamental Design for a Vehicle-Tire, of which the following is a specification, reference being had to the accompanying drawings, forming part thereof.

Figure 1 is a plan view of a portion of the tire illustrating my new design. Fig. 2 is a sectional view through my tire, the plane of section being indicated by the line 2—2 of Fig. 1.

I claim:

The ornamental design for a vehicle tire substantially as shown and described.

DANIEL L. BECKER.
